(57) **CLAIM**

The ornamental design for a modular electronic housing, as shown and described.

DESCRIPTION

The Modular Electronic Housing Thereof includes modular electronic housings intended to be used to house electronic circuit board and their included electronic components. The modular housings can be assembled into groupings of electronic housings as illustrated.

FIG. 1 is a right side perspective view of a modular electronic housing showing our new design.

FIG. 2 is a left side elevational view thereof;

FIG. 3 is a top plan view thereof; and,

FIG. 4 is a bottom plan view thereof.

The broken line disclosures in the drawings are for illustrative purposes only and form no part of the claimed design.
